US00D995491S

(12) **United States Design Patent** (10) **Patent No.:** **US D995,491 S**
(45) **Date of Patent:** **** Aug. 15, 2023**

(54) **EARPHONE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/881,538**

(22) Filed: **Jan. 3, 2023**

Related U.S. Application Data

(63) Continuation of application No. 29/837,465, filed on May 5, 2022, now Pat. No. Des. 975,066, which is a continuation of application No. 29/805,722, filed on Aug. 30, 2021, now Pat. No. Des. 951,234, which is a continuation of application No. 29/768,810, filed on Feb. 1, 2021, now Pat. No. Des. 929,376, which is a

continuation of application No. 29/706,556, filed on Sep. 20, 2019, now Pat. No. Des. 909,347, said application No. 29/805,722 is a continuation of application No. 29/768,818, filed on Feb. 1, 2021, now Pat. No. Des. 929,972, which is a continuation of application No. 29/706,556, filed on Sep. 20, 2019, now Pat. No. Des. 909,347.

CLAIM

The ornamental design for an earphone, as shown and described.

DESCRIPTION

FIG. 1 is a front perspective view of an earphone showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the earphone that form no part of the claimed design.
